(**) Term: **14 Years**

(57) **CLAIM**

The ornamental design for a combined digital disc player and automotive navigation system, as shown and described.

DESCRIPTION

May 16, 2005 (JP) 2005-013916

FIG. 1 is a perspective view of a combined digital disc player and automotive navigation system showing our new design;

(51) **LOC (8) CI.** **14-01**

FIG. 2 is a perspective view showing the control panel opening thereof;

(52) **U.S. CI.** **D14/157; D14/257**

FIG. 3 is a front view of FIG. 1;

(58) **Field of Classification Search** D14/496,

FIG. 4 is a rear view thereof;

D14/157, 257-258; D10/65, 80; D12/192;

FIG. 5 is a right side view thereof, the left side view being a mirror image of the right side view;

455/344-351; 701/200, 213, 214, 216, 221;

FIG. 6 is a top plan view thereof;

340/770, 995.28

FIG. 7 is a bottom plan view thereof;

See application file for complete search history.

FIG. 8 is a front view of FIG. 2;

(56) **References Cited**

FIG. 9 is a right side view thereof;

U.S. PATENT DOCUMENTS

FIG. 10 is a perspective view showing the front panel opening thereof; and,
